UNITED STATES PATENT OFFICE

CLINTON H. M. BULL, OF HOUSTON, TEXAS, ASSIGNOR TO REED ROLLER BIT COMPANY, OF HOUSTON, TEXAS, A CORPORATION OF TEXAS

DRILL BIT

Application filed November 26, 1927. Serial No. 235,806.

This invention relates to deep well drilling apparatus, and more particularly to drill bits.

The invention has for one of its objects the provision of new and improved locking means for the separable parts of a two-piece bit head.

Another object is to provide a new and improved roller cutter mounting.

Further objects will hereinafter appear.

In the accompanying drawings, which are illustrative of the preferred embodiment of the invention, Fig. 1 is a partly sectional side elevation of the assembled bit; Fig. 2, a horizontal section on the line 2—2 of Fig. 1; Fig. 3, a section on the line 3—3 of Fig. 1; and Fig. 4, a detail side view of the cutter bushing or support.

Referring more specifically to the drawings, the longitudinally divisible bit head is indicated at 1, the meeting faces of the two parts of said head being recessed for the reception of a pipe 2 having an annular flange 2^a to rest upon the upper, screw-threaded shank formed by the union of the parts. The pipe 2 may be held in place by threads 2^b, or otherwise.

The two parts of the head are held together by bolts 3 and 4, both of which have eyes through which pipe 2 extends, the meeting faces of the two parts of the head being suitably recessed to receive the enlarged inner ends of said bolts. It will be obvious to those skilled in the art, that when nuts 3^a and 4^a are tightened, the respective bolts will be moved outwardly to firmly grip the pipe 2, and hold the two parts of the head securely together. And it will be noted that to separate the two parts of the head it is not necessary to remove the bolts. The bolts need only be loosened to permit withdrawal of pipe 2, which serves as a locking pin, and the withdrawal of which renders the two parts of the head easily separable.

The head may be provided with dowel pins 5 for the guidance of the parts into alignment, and to hold the same against movement with respect to each other.

Keys 6 may be used to prevent rotation of the bolts in their respective parts.

It will be understood that any equivalent

locking pin may be used in place of the pipe 2, but the use of the pipe 2 is particularly desirable because it provides a removable slush or water course through the head to discharge water upon the cutters and effect removal of the cuttings.

The head may be spirally grooved as shown at 7 to provide a free upward passage for slush laden with cuttings during drilling operations.

The beveled lower ends of the two parts of the head define a substantially V-shaped cutter recess, said ends being provided with integral spindles 8, which project downwardly and inwardly toward the longitudinal axis 65 of the head.

The bushings or cutter supports 8 may be screw-threaded upon spindles 9. Each of these bushings has a cylindrical portion circumferentially grooved as shown at 9^a, the side walls of the groove being inclined outwardly to form with tapered sectional rings 10 raceways for balls 11. The cutter 12 is provided with opposite raceways, as shown.

The parts may be assembled as follows: 75 The bushing 9 is screwed on spindle 8, and the rings 10, which are laterally slidable in groove 9^a, are moved toward each other so that the balls 11 may be placed as shown by Fig. 4 and held in place by grease or the like. It 80 will be observed that the outer surfaces of said balls are then substantially flush with the outer sides of the bushing. The cutter 12 may, therefore, be slipped on the bushing. The plugs 13, screw-threaded in openings in the side of the cutter 12, and provided with pointed inner ends, are then screwed inwardly between said rings. The rings, forced apart by the wedge plugs, force the balls outwardly so that said balls enter the raceways 90 in the cutter. The cutter is thus securely and rotatably locked on the busing.

The device disclosed by the drawings and above described, is the preferred embodiment of the invention, but it is to be understood that various changes may be made within the scope of the following claims.

I claim:

1. A bit head having a plurality of parts, eye bolts secured to said parts, and means ex- 100

tending through the eyes of said bolts to hold said parts together.

5. A bit head having a plurality of parts, eye bolts secured to said parts, and a pipe extending through the eyes of said bolts to hold said parts together.

10. A bit head longitudinally divided into a plurality of parts, the lower ends of said parts being beveled to form a cutter recess, cutters carried by said ends, eye bolts secured to said parts, and means extending through the eyes of said bolts to hold said parts together.

15. A bit head longitudinally divided into a plurality of parts, the lower ends of said parts being beveled to form a cutter recess, cutters carried by said ends, eye bolts secured to said parts, and a pipe extending through the eyes of said bolts to hold said parts together.

20. A bit head longitudinally divided into two parts, eye bolts carried by said parts, the eyes of said bolts being innermost, and a removable pipe extending through said eyes, to hold the parts of said head together, the meeting faces of said parts being recessed for the reception of said pipe and eyes.

25. A bit head longitudinally divided into two parts, the meeting faces of said parts being recessed to form a central water course, a removable water pipe in said course, and eye bolts carried by said parts, said pipe extending through said eyes to hold the parts of said head together.

30. 7. A bit head longitudinally divided into two parts, the lower ends of said parts being beveled to form a cutter recess and having integral spindles thereon extending downwardly and inwardly toward the longitudinal axis of the head, said parts being grooved to form a central water course communicating with said recess, a removable water pipe in said course, and eye bolts carried by said parts, said pipe extending through the eyes of said

45. bolts to hold said parts together.

In testimony whereof, I hereunto affix my signature.

CLINTON H. M. BULL.
